STOP MECHANISM FOR KNITTING MACHINES

Filed Jan. 29, 1931

UNITED STATES PATENT OFFICE

JACOB WACHSMAN, OF BROOKLYN, NEW YORK

STOP MECHANISM FOR KNITTING MACHINES

Application filed January 29, 1931. Serial No. 512,153.

My invention relates to knitting machines and particularly to the mechanism employed for actuating the stop handle of the drive mechanism of the machine when a thread breaks or the end of a thread has been 5 reached, etc.

The invention has for an object to provide an improved controller mechanism associated with the stop handle and electrically released by the breaking of the thread or when 10 an end of a thread is reached as when the bobbin becomes empty.

Further, the invention has for an object the provision of a controller unit which can 15 be used in almost any position on the knitting machine wherever the stop handle may be located, and one which will operate either to pull down or push up the stop lever according to the particular direction in which that 20 lever must be moved to stop the machine.

Further, the invention has for an object to provide a controller which, when set and also after its release, will be on open circuit so 25 that the attendant cannot get an electric shock should he touch the controller.

Other objects will in part be obvious and in part be pointed out hereinafter.

To the attainment of the aforesaid objects and ends, the invention still further resides 30 in the novel details of construction, combination and arrangement of parts, all of which will be first fully described in the following detailed description, then be particularly pointed out in the appended claims, reference being had to the accompanying drawings, in which:

Figure 1 is a perspective view of the controller in the "set" position.

Figure 2 is a vertical section on the line 40 2-2 of Figure 1.

Figure 3 is a face view of the latch and magnet box with cover removed.

Figure 4 is a perspective view of an end detector unit used as a circuit closer in cooperation with my controller.

Figure 5 is a circuit diagram of the electric circuit involved.

In the drawings, in which like numerals of 50 reference indicate like parts in all of the figures, 1 represents the leg or supporting

frame of a knitting machine to which the controller is secured and 2 indicates the stop handle of the driving mechanism that throws the clutch or shifts the drive belt that stops the machine. 3 represents the base of the controller from which attaching lugs 4 and 5 (having suitably bushed holes) project and at either end the base has webs 6 (top) and 7 (bottom), these webs being provided with square openings 10 constituting bearings for 55 the longitudinal plunger bar or rod 11.

The base 3 is also provided with a longitudinal slot 8 and one or more sets of holes 9 bushed with insulation.

The plunger bar at either end is provided 60 with stop handle engaging arms 12, 13 and 14, and the instrument may be so set that either one of these arms will engage the stop handle, the particular arm for engaging the stop handle being determined by the position in 70 which the base 3 may be mounted on the machine.

15 is a latch pawl which is pivoted at 16 to the rod 11 and projects through the slot 8, there being a spring 17 on the rod 11 for 5 the purpose of impelling that rod in a direction to cause actuation of the stop handle 2.

18-18x is a suitable metallic box that is secured to and insulated from the base 3 on the side opposite the place where the bar 11 is 80 located. This box includes a front plate 19 and in this box is rockably mounted a rockable locking member 20 which is pivoted on a rod or shaft 22 (mounted in the box 18-18x) and is impelled to a holding position by a 85 coil spring 21.

Suitable bearings 23 are provided for the rod 24 which carries a latch lever 25, the latter being arranged to cooperate with the armature 29, the armature holding the latch 90 lever 25 against movement when the electromagnet 28 is de-energized. 26 is a latch lever moving rocker member which engages with the latch lever 25 and is itself engaged by a pin 27 on the rockable locking member 95 20.

When the parts are in the position shown in Figure 2 the member 20 is held against movement by means of the elements 25, 26 and 27.

The latch lever 25 has a slotted arm 25y to leave a lip 25z which laps over the armature lip 29z normally. The lever 25 has an arm 25y which, together with the body of the lever 25, forms a V-shaped recess for the end of the lever rocking member 26. The member 26 is pivoted at 26z and has a recess for the pin 27. When the magnet 28 is de-energized the parts remain as positioned in Figures 2 and 3. When, however, the magnet is energized it draws over the armature 29 until its lip 29z lines up with the arm 25y, whereupon the lever 25 is free to be moved. The pressure of the spring 17 acting through the pawl 15 is imparted to the rockable member 20 to turn it in a counterclockwise direction in Figure 2. This causes the pin 27 to rock the member 26 in a counterclockwise direction in Figure 2 and thereby effects engagement with the member 25y to move it in a clockwise direction in Figure 2. This carries the notched end of the lever 25 up alongside the armature free from the holding influence of the armature. As soon as member 15 shall have released itself from member 20, spring 21 will move member 20 in a clockwise direction in Figure 2; pin 27 will again engage the recess in member 26 and turn that member in a clockwise direction in Figure 2, which causes the member 26 to press down on the lever 25 and bring its end 25z again below the armature portion 29z, whereupon the armature springs back to the position shown in Figure 3 and again locks the member 25 against movement.

One terminal of the electro-magnet is connected to an insulated terminal 30 carried by the box while the other terminal of the magnet is grounded to the box as at 31, it being understood that the box 18 is made of a conducting material.

The circuit closer which may be used to actuate the magnet 28 may be an end detector consisting of a mounting plate 32 having one or more slots 33, and mounting ears 34 as best shown in Figure 5. 35 is a foot which carries one or more porcelain bushed eyes 36 through which the thread is passed while 37 indicates a tension device which may or may not be used as found desirable. The plate 32 has one or more slots 33 through which porcelain eyes 39 that are carried by the pivoted arm 38 may be projected so that the thread can be passed through it, and when so passed through, it holds the circuit open between the contact heel 41 and the insulated contact spring 43, the latter being mounted on the box 42. 40 is the pivoted axis of the arm 38.

Referring now to Figure 5 it will be seen that the battery 45 has one terminal connected via wire 44 with the insulated spring 43, while its other terminal is connected via wire 46 to the insulated terminal 30.

The plate 32 of the end detector is

grounded to the frame of the machine as is also the rod 11. Thus, when the circuit is closed between the contacts 41 and 43 as when the end of the thread passes through the eye 39, or the thread breaks and releases the eye 39, current will flow from the battery through the circuit to energize the magnets 28 (it being assumed, of course, that the controller is set with the rockable locking member 20 and the latch pawl 15 in contact) thereby energizing the electro-magnet and releasing the latch lever 25, the latch lever 25 being released, the spring 17 will force the rod 11 in a direction to disengage the latch pawl 15 from the rockable locking member 20 and bring one or another of the stop handles 12, 13 and 14, as the case may be, into operative engagement with the stop handle 2 to stop the machine.

It will be noted that when the controller is set and the machine is running properly the circuit will be open between the elements 41 and 43 and immediately after the circuit has been closed by those elements to energize the magnet 28, the circuit will be broken between the elements 15 and 20. Thus the circuit is closed only for an instant and at all other times the controller is on open circuit so that there is no danger of an attendant getting a shock when he attempts to re-set the controller.

The box 18 may be mounted in a variety of positions on the base 3 and the latch pawl 15 may be reversed at times to correspond with a reverse mounting of the box, thus making it possible to apply the device to almost any type of knitting machine, since the base 3 is not required to be mounted in one particular position.

From the foregoing description, taken in connection with the accompanying drawings, it is thought the complete construction, operation and advantages of my invention will be clear to those skilled in the art to which it relates.

What I claim is:

- In electric stop mechanism for power driven machines, the combination with a circuit closer, of a controller comprising a base having provisions for mounting it on the machine and having end portions provided with rod apertures, said base being longitudinally slotted, a rod longitudinally movably mounted in said apertures, a latch pawl mounted on said rod, a rod impelling spring cooperating with said rod, a box mounted on said base and containing an electro-magnetically releaseable locking member, the latter cooperating with said pawl to hold said rod in a "set" position, stop-handle-engaging means carried by said rod for throwing the stop handle of the power driving mechanism to a "stop" position when said rod is released, and an electric circuit including a source of energy, said circuit closer, and

the electro-magnets of said electro-magnetically releasable locking mechanism.

2. In electric stop mechanisms for power driven machines wherein is provided a circuit closer controlled by the material being operated on and wherein is provided a stop handle; a controller for actuating said stop handle, said controller comprising a base plate having top and bottom webs apertured to provide bearings, a rod reciprocably mounted in said bearings, a spring to move said rod in one direction, stop-handle-engaging means carried by said rod, a latch pawl on said rod, said base having a longitudinal slot into which said pawl projects, a box secured to said base and containing a rockable locking member to be engaged by said pawl to hold said rod against movement, an electro-magnet, an armature, means connecting said rockable locking member with said armature to be held against movement thereby, said armature when effected by said magnet serving to release said connecting means.
3. In electric stop mechanisms for power driven machines wherein is provided a circuit closer controlled by the material being operated on and wherein is provided a stop handle; a controller for actuating said stop handle, said controller comprising a base plate having top and bottom webs apertured to provide bearings, a rod reciprocably mounted in said bearings, a spring to move said rod in one direction, stop-handle-engaging means carried by said rod, a latch pawl on said rod, said base having a longitudinal slot into which said pawl projects, a box secured to said base and containing a rockable locking member to be engaged by said pawl to hold said rod against movement, an electro-magnet, an armature, means connecting said rockable locking member with said armature to be held against movement thereby, said armature when effected by said magnet serving to release said connecting means, means for insulating said box from said base, one terminal of said magnet being grounded to said box, an insulated terminal connection carried by said box to which the other terminal of said magnet is connected, and an electric sub-circuit including a source of energy, and a circuit closer, one terminal of which sub-circuit is connected with said base and the other terminal of which is connected to said insulated terminal.

JACOB WACHSMAN.
